UNITED STATES PATENT OFFICE.

ROBERT W. NEWTON, OF PROVIDENCE, RHODE ISLAND, ASSIGNOR TO THE GENERAL FIRE EXTINGUISHER COMPANY, OF NEW YORK, N. Y., A CORPORATION OF NEW YORK.

AUTOMATIC FIRE-EXTINGUISHER.

SPECIFICATION forming part of Letters Patent No. 728,280, dated May 19, 1903.

Application filed December 31, 1897. Serial No. 667,376. (No model.)

To all whom it may concern:

Be it known that I, ROBERT W. NEWTON, of the city and county of Providence and State of Rhode Island, have invented certain new

and useful Improvements in Automatic Fire-Extinguishers, (for which I have obtained a patent in Great Britain, No. 12,775, dated June 10, 1896, and a patent in France, No. 262,019, dated December 9, 1896;) and I do hereby declare the following specification, taken in connection with the accompanying drawings, forming a part of the same, to be a full, clear, and exact description thereof.

This invention has reference to improvements in the construction of automatic fire-extinguishers adapted to be released by the action of heat and to distribute water in the form of spray over a large area.

Automatic fire-extinguishers form the most reliable protection against great loss by fire. With an intelligently-designed installation by which the full force of the water will when a fire starts act on any sprinkler that may be opened by the heat the fire will be instantly arrested, confined to the place where it started, and quickly extinguished, provided the sprinklers or automatic fire-extinguishers are sufficiently sensitive to heat to open quickly and throw a spray of water around the freshly-starting fire.

One object of this invention is to so construct a sprinkler that the rising temperature caused by a fire in the vicinity of the sprinkler will act more readily on the fusible solder and release the valve so promptly that a mere incipient fire will open the nearest sprinkler and cause a spray of water to inclose and extinguish the fire.

Another object of the invention is to expose the fusible joint of the automatic sprinkler to the rising currents of heated air caused by an incipient fire, and thereby more quickly release the valve.

Another object of the invention is to produce an automatic sprinkler which while much more sensitive to heat firmly resists the pressure on the valve, is not liable to leak, and not liable to stick when partly opened; and another object of the invention is to so

construct the soldered holding devices that they may be easily attached to the valve-holding device and new ones substituted after a fire.

To these ends the invention consists in the peculiar and novel construction of an automatic fire-extinguisher or sprinkler shown in the drawings and hereinafter more fully described.

The terms "automatic fire-extinguisher," "sprinkler," and "automatic sprinkler" for the purpose of this specification are synonymous.

Figure 1 is a side view of my improved automatic fire-extinguisher, showing the same in the closed position. Fig. 2 is a vertical sectional view of the automatic fire-extinguisher at right angles through the vertical center of Fig. 1. Fig. 3 is a bottom view of the hollow supporting-block and the overlapping frame, by which the valve-supporting struts are held until released by heat. Fig. 4 is a side view of the hollow supporting-block, the braces or struts by which the valve is held, and the overlapping frame, shown in section. Fig. 5 is an end view of the hollow supporting-block, the struts, and the overlapping frame, shown partly in section. Fig. 6 is a bottom view of the hollow supporting-block and a modified form of frame having the inclined vertical sides secured together by solder fusible at a low temperature. Fig. 7 is a side view, partly in section, showing the modified frame in connection with the hollow block and the thrust-struts. Fig. 8 is an end view of the hollow block, the struts, and the modified form of overlapping frame.

In the drawings, A designates a screw-threaded nozzle adapted to be secured in the usual pipe-fittings used in a fire-extinguisher installation. When open, it forms the discharge-outlet from the system. This nozzle is provided with the flange B, from which extends the frame C, having the conventional form of a Gothic arch, the cone D forming the keystone to the arch. Against the cone D is secured the dished deflector E by means of a nut F', engaged with the adjusting-screw F, the upper end of which forms the thrust-

support of the hollow block G, formed of sheet metal, so as to allow the heated air to pass around and through the same. The block G forms the support for the struts H, 5 which incline toward each other and support the valve I, by which the discharge-opening of the nozzle A is closed. To firmly support the valve I against internal pressure in the installation, the lower ends of the struts H H, 10 forming the base, must be held against spreading apart. To do this effectually, I use two forms of frames, one form being shown enlarged in Figs. 3, 4, and 5 and the other in Figs. 6, 7, and 8. 15 Referring now to all the figures except Figs. 6, 7, and 8, K K designate two U-shaped plates of sheet metal. These are placed one on top of the other with the arms overlapping and are soldered together with the solder used in 20 automatic fire-extinguishers, which is fusible at a temperature but little higher than the temperature normally existing in the room to be protected. When secured together, the two U-shaped plates form a rectangular frame 25 against the inner end pieces of which the struts H H bear. The plates K have the lips L bent down on each end to hold the frame in place. The solder joint in the frame is strengthened by the use of the balls M, which 30 also insure the separation of the plates as soon as the solder is weakened by heat. The balls M M are inserted into holes in the arms of the U-shaped plates K, made slightly concave. When the solder weakens, the strain 35 on the opposite ends of the two U-shaped plates K K, forming the frame, causes the balls to turn and enter between the plates, thus separating the soldered surfaces.

In the modified form shown in Figs. 6, 7, 40 and 8 the plates K' are vertical. They are bent up into the U shape, and their vertical flat sides are secured together by solder. They are preferably bent so that the solder joint is inclined to facilitate the ready separation of the parts. The balls M M may be 45 used with this solder joint in the same manner as in the frame of the preferred form. In the frame of the modified form a portion of the vertical plates at each end are bent at 50 right angles to form the plates n n, which rest on the block G. The lips l l are bent over the plate of the block G to secure the frame.

The soldered portions of the U-shaped plates K K', forming the retaining-frame, are 55 placed outside the block G, so that the heated air can pass between them and the parts of the sprinkler to which the frame is connected, as is shown in Figs. 5 and 8 by arrows. By thus separating the solder joint from the 60 sprinkler the joint is much more readily affected by the rising heated air, and the sprinkler is more sensitive, being released much quicker.

An automatic fire-extinguisher installation 65 provided with automatic sprinklers such as herein described will protect a cotton-picker room, or a room in which naphtha or other

gas is liable to explode against loss by fire, such sprinklers being so sensitive to heat that an explosion will instantly release most 7c of the sprinklers and arrest any fire in its incipiency.

Having now particularly described and ascertained the nature of my said invention and in what manner the same is to be performed, 75 I declare that what I claim is—

1. In an automatic fire-extinguisher, the combination, with the nozzle, of a valve for closing the nozzle, a thrust-block, the inclined struts and a separate two-part frame secured 80 together with fusible solder and having flat end portions resting upon the thrust-block and constituting means for engaging the lower ends of said struts, substantially as described. 85

2. In an automatic sprinkler, the combination, with the nozzle, the frame, the distributor, and the valve for closing the nozzle, of a strut, a thrust-block, and a separate two-part frame secured together by solder and 90 provided with lips for securing said frame to the thrust-block, substantially as described. 95

3. The combination, as herein set forth, with the nozzle, the arched frame, the distributor and the valve-disk of an automatic sprinkler, 95 of the adjusting-screw F, the hollow block G, the struts H, H, and the U-shaped plates secured together by solder the soldered parts of which extend outside of the hollow block whereby the heated air more readily affects 100 the solder, as described.

4. In an automatic fire-extinguisher, the combination with the nozzle, the valve, disk for closing the nozzle-outlet the arched frame C, the cone D, the screw F, the distributor E secured by the nut F', of the hollow block G the interior and exterior of which is exposed to the air, the struts H, H, and the frame composed of the U-shaped plates, secured together by solder and provided with the lips, 105 by which the plate is secured to the hollow block, as described. 110

5. In an automatic fire-extinguisher, the combination with the nozzle A, the arched frame B, the valve I for closing the nozzle, the screw F and a deflecting distributor, of the struts H, H, the hollow metal block G, and the frame K, consisting of bent vertical plates secured together at the adjacent vertical planes by solder fusible at a low temperature, said soldered plates extending along the sides of the hollow block and away from the same, whereby the heated air has free access to the soldered plates and the sprinkler is released more quickly on the breaking out 120 of a fire, as described. 125

6. In an automatic fire-extinguisher, the combination with the nozzle, of a valve for closing the nozzle, a thrust-block, two struts having their upper ends inclined toward each other and engaging the valve and their lower ends resting on said thrust-block, and a separate two-part frame having flat end portions resting upon the thrust-block and forming 130

abutments for engaging the lower ends of said struts, and preventing said ends from spreading apart, the parts of said frame being held together by fusible solder, substantially as described.

7. In an automatic fire-extinguisher, the combination with the nozzle, of a valve for closing the nozzle, a thrust-block, struts as H H, U-shaped plates having their arms set 10 cured together by fusible solder and forming a rectangular frame having flat end portions resting upon the thrust-block and constituting means, for holding said struts, substantially as described.

8. In an automatic fire-extinguisher, the combination with the nozzle, of a valve for closing said nozzle, struts as H H, a thrust-block, and a separate frame formed of two plates secured together by fusible solder and having flat end portions resting upon the 15 thrust-block and forming abutments for engaging the ends of said struts and preventing them from spreading apart, substantially as described.
